UNITED STATES PATENT OFFICE

135,584

DESIGN FOR A TENT STAKE

Donald A. Wallance, Washington, D. C.

Application March 1, 1943, Serial No. 109,639

Term of patent 3½ years

To all whom it may concern:

Be it known that I, Donald A. Wallance, an employee of the United States Government, a citizen of the United States, residing at 2020 19th St. Place NE., Washington, D. C., have invented a new, original, and ornamental Design for a Tent Stake, of which the following is a specification, reference being had to the accompanying drawing, forming part thereof.

Fig. 1 is a front elevational view of a tent stake, showing my new design.

Fig. 2 is a side elevational view,
Fig. 3 is a rear elevational view, and
Fig. 4 is a plan view thereof.

I claim:

The ornamental design for a tent stake, as shown.

DONALD A. WALLANCE.
